UNITED STATES PATENT OFFICE

2,609,486

CHIMNEY ASSEMBLY FOR MINERS' SAFETY LAMPS

Grant Wheat and Arthur G. Davis, Marlboro, Mass., assignors to Koehler Manufacturing Company, Marlboro, Mass., a corporation of Massachusetts

Application December 20, 1948, Serial No. 66,368

1 Claim. (Cl. 240—18)

1

This invention relates to miners' lamps of the type commonly referred to as "safety flame lamps."

In general, such a lamp includes a fount for holding a supply of kerosene, or other liquid fuel; a burner of the wick type; a substantially non-breakable glass chimney encircling the wick; a bonnet above the chimney; a dome top above the bonnet; and means for holding these parts together in their assembled relationship.

The present invention aims to improve lamp structures of this type with a view to facilitating the servicing and maintaining operations, devising a construction which will be simpler and more economical to manufacture, and one that will be more convenient to use.

Lamps of this type customarily are equipped with a spark igniter which is operated by hand. The usual constructions have been relatively cumbersome, occupy considerable space in the fount, and are difficult to remove. It is one of the objects of the present invention, therefore, to devise a construction in which these objectionable characteristics will be eliminated.

The nature of the invention will be readily understood from the following description when read in connection with the accompanying drawings, and the novel features will be particularly pointed out in the appended claim.

In the drawings,

Fig. 1 is a vertical, sectional view, partly in elevation, of those parts of a lamp structure with which this invention is more especially concerned;

Fig. 2 is a plan view of the fount with the burner and igniter in place;

Fig. 3 is an exploded view of a novel form of igniter provided by this invention;

Fig. 4 is a vertical, sectional view through the fount showing the manner in which the igniter is supported in it;

Fig. 5 is a fragmentary plan view of a part of the top plate of the fount; and

Fig. 6 is a side elevation of a small portion of the top ring and the edge of the dome plate.

Referring first to Fig. 1, the lamp structure there shown comprises a fount 2 which may be of the usual construction. It is provided with an integral annular neck 3 rising from its top and this neck is slotted at several points, some of which are shown at 4, for the passage of air therethrough. Resting on the fount inside of the neck is an air admission ring 5, which may also be of the usual form, and it is shaped to provide a seat for the bottom of the glass chimney 6, a gasket 7 being interposed between said seat

2

and the lower end of the chimney. On top of this chimney is another ring 8 carrying a gasket 9. The flanged lower end of the inner gauze cone 10 rests on this ring 8 while the flanged and cupped lower end of the outer gauze cone 12 is seated on the flange of the inner cone.

Surrounding these cones is a bonnet 13 resting at its lower end on a middle ring 14 similar to those used heretofore, and supported on the top 10 of this bonnet is a top ring 15, both of the rings 14 and 15 having numerous holes for the passage of air therethrough. At the extreme top of the lamp structure is a dome top 16, covering the upper open end of the bonnet, and the usual carrying hook 17 is attached to it.

In order to secure these main portions of this lamp superstructure rigidly together, several rods 18, in this instance five, preferably made in the form of elongated bolts, are arranged to connect 20 the top and bottom elements of this assembly. As shown, each of these rods is provided with a slotted head positioned in a countersunk hole formed in the lower side of the lock ring 20 which is screw-threaded on the neck 3 of the fount. A 25 series of tubes 21, each encircling a portion of one of the rods 18, is interposed between the lock ring 20 and the middle ring 14 where they space these two elements apart. The middle and top rings are spaced apart by the bonnet 13. Above 30 the bonnet several short tubes 22 encircle the upper portions of the respective rods 18 and space the dome top 16 from the top ring 15 by a distance ample to provide ventilation. Nuts 23, threaded on the upper ends of the rods 18 serve, 35 when turned up, to tighten the parts of the entire bonnet and frame assembly rigidly together. Between the middle ring 14 and the adjacent flange of the outer cone 12, a spring ring or 40 expansion ring 26 is inserted where it serves to compensate for any expansion or contraction of the parts due to changes in temperature and to maintain the joints in the assembly tight.

This construction simplifies the superstructure of the lamp, makes it more reliable and less likely to get out of order, and it provides a very rigid 45 top unit convenient to handle in unscrewing the fount from it, as is necessary in connection with the frequent refilling and other maintenance operations. The fount is filled through an opening in its top normally closed by the screw-threaded plug 19, Fig. 2. Servicing of the lamp includes, in addition to refilling, the cleaning of the chimney 6, the bonnet and cones, and the 50 inspection and cleaning of the wick and the igniter. In re-assembling the parts after cleaning, the bolts 18 are checked to be sure that they 55

are tight, and the fact that there are only five of these bolts, as compared to a much larger number required in prior constructions, plus the further fact that the chief inspection of them consists in trying them with a screw-driver at the bottom of the ring 20 in order to see if they are tight, reduces the work involved and eliminates some of the opportunities for error of inspection.

It should be noted that the heads of the bolts 18 are concealed within the rings 20 when the assembly is in its normal or operative condition, which protects them against tampering. However, when the fount is removed these screws are readily accessible so that they can be tightened in connection with the matter of replacing the parts after the routine cleaning operation has been performed. Each of the nuts 23 at the upper ends of the bolts is seated in a depression or socket formed in the dome top 16 which prevents the nut from rotating.

While some type of lock usually is provided to prevent the separation of the lamp top from the fount, the present invention does not interfere in any way with the use of any of the common forms of locking devices and none, therefore, has been illustrated in this application.

As above indicated, a further feature of this invention resides in the mounting of the igniter. This unit preferably is of the spark type, including a friction wheel or disc *a*, Fig. 4, provided with a file-cut edge working against a piece of flint or pyrometal *b* housed in the tube *c*. In the construction provided by this invention the holder 25 for the parts just mentioned is of cylindrical shape and it has a flat bottom to rest on the top plate of the fount 2. Supported in this fount is a receiver 27 of generally tubular form which extends through the body of the fount and is sealed at opposite ends to the top and bottom of the latter. It is desirable to have the igniter occupy a position no higher than the burner 24 when the lamp is in operation and, consequently, it is necessary in lighting the lamp to raise the igniter into such a position that the spark produced by the operation of the latter will be on approximately a level with the top of the wick *w*, Fig. 2. A port *d*, Fig. 4, is formed in the side of the igniter holder 25 through which the flash is directed across the top of the wick. At the same time it is important to be able to remove the igniter readily for cleaning, replacement, or repairs, and it is absolutely essential that there shall be no leakage of air from the outside through the igniter or around its operating element.

To satisfy these requirements the igniter support or body 25 is provided with an integral stem which extends down into the upper hollow end of the receiver 27. This stem comprises two flat-sided bosses 28 and 29 spaced apart by an intermediate cylindrical part 30. A shaft 31, which by cam action operates the friction wheel shaft, extends through the body and the stem and terminates at its lower end in a threaded section 32 to receive the operating knob 33. A coiled spring 34 encircles the shaft 31 when the parts are in their operative positions, as shown in Fig. 4, and it abuts at its upper end against the shoulder in the receiver 27 and at its lower end against the inner end of the knob. Consequently, this spring normally holds the igniter in its lowered position where the body 25 rests on the upper plate of the fount.

In operating the igniter the knob 33 is turned

in a clockwise direction which rotates the friction wheel or disc *a* up to a certain point at which its connection with the shaft is released, and a spiral spring connected with the disc then operates through the energy stored in its by the previous rotation of it to give the disc a quick rotative movement in the opposite direction, which operates by its contact with the flint or pyro-element *b* to produce the flash that lights the wick. Prior to operating the knob 33 it has been pushed upwardly, carrying the igniter up with it, and the knob is released immediately after the flash has occurred, whereupon the spring 34 returns the knob and the igniter to their original positions.

During the upward movement of the knob and the igniter the boss 28 slides through a hole 35 in the top plate of the fount, and this hole is of such shape and dimensions as to fit snugly around the boss 28 with a suitable operating clearance. The boss 29 is of the same peripheral shape and dimensions as the boss 28, and it serves as a stop to engage the top plate of the fount and so limit the upward movement of the igniter that such movement will be arrested when the igniter is in the correct position to light the wick. It may here be observed that the igniter support 25, the bosses 28 and 29, and the intermediate member 30, are all coaxial with the shaft 31, and the curved surfaces of the bosses are concentric with those of the parts 25 and 30.

Occasionally it is necessary to remove the igniter from the fount and this operation can be performed by turning the knob 33 counter-clockwise and thereby unscrewing it from the shaft 31, after which the igniter body can be lifted until the boss 29 strikes the bottom of the top plate of the fount. Then by giving it a quarter turn in a counter-clockwise direction the lower boss 29 is brought into the proper position to pass through the hole 35. The whole igniter body then can be lifted out and replaced with a new one, or suitable repairs made, as may be necessary. However, the lower boss is important in preventing the igniter from falling out of the fount if the lamp should be turned upside down at a time when the knob 33 has been removed.

In replacing the igniter the lower boss 29 is fitted in the hole 35 and drops down until the shoulder on the bottom of the boss 28 strikes the top plate of the fount. Then the igniter is turned in a clockwise direction until the upper boss registers completely with the hole and drops into it.

Thus it will be observed that in order to remove the igniter from the fount, it is necessary not only to remove the knob but also to produce both slideable and rotative movements, of predetermined degree, of the igniter body in order to effect its release. It should be observed that the flat on the boss 28 is at right angles to the axis of the igniter tube *c*, while the flat on the lower boss 29 is parallel with that axis. The flat in the hole 35 is at right angles to the axis of the tube when the igniter is in its operative position, as shown in Fig. 2. Consequently, if the operating knob should be removed with the rest of the lamp still assembled and lighted, it would be impossible to raise the igniter far enough to free it from the hole 35. Also, the rotative movement of the igniter essential to its removal would be prevented by the igniter tube striking the inner wall of the glass chimney 6. This will be clearly seen from an inspection of Fig. 2.

Such a condition is important because if the igniter could be pushed up out of the fount

merely by removing the knob, a hole would be provided through which surrounding air and gases could flow into the wick chamber inside the chimney 6, and if these gases were combustible, an explosion might be produced.

A further provision made for the purpose of preventing the entrance of combustible gases into the lamp consists in providing the restriction 36 in the bore of the tubular receiver 27. That is, this bore is so restricted immediately above the spring 34 that it closely encircles the shaft 31 and prevents any appreciable leakage of gases around this operating element for the igniter and into the wick chamber.

While we have herein shown and described a preferred embodiment of our invention, it is contemplated that the invention may be embodied in other forms without departing from the spirit or scope thereof.

Having thus described our invention, what we desire to claim as new is:

In a miner's safety lamp, a fount having an externally threaded flange set inwardly from its upper marginal edge, a lock ring in threaded engagement with said flange and having bolt sockets in its under face and bolt openings extending vertically from said sockets, said lock ring being adapted to have its under face seated upon the upper marginal edge of said fount to close said socket openings, transverse air ports formed in the bottom of said flange, an air admission ring seating on said fount inward of said flange, said ring being formed with a lateral annular shoulder, a chimney supported on said shoulder, a gauze cone supported on the top of said chimney 35 having an outwardly flanged bottom portion, a

perforated ring supported upon said cone shoulder, the perforations in said ring being vertically aligned with the bolt openings in said lock ring, a hood supported on said ring outwardly of said

- 5 perforations, a top ring on said hood, and a dome formed with perforations aligned with the perforations in said first ring and said lock ring, said dome being depressed adjacent its perforations to form nut shrouds, bolts having their heads seated in the bolt sockets in said lock ring and extending through said rings and dome, said bolts having associated nuts seated in the shrouds in said dome and adjusted by operation of their heads in said lock ring, and tubular supports of greater diameter than said bolts enclosing exposed portions of the latter, said tubular supports being supported at their lower ends upon said lock ring and having their upper ends in supporting engagement with said perforated ring.

GRANT WHEAT.
ARTHUR G. DAVIS.
